UNITED STATES PATENT OFFICE

91,806

DESIGN FOR A SIGN

Soren A. Egekvist, Minneapolis, Minn.

Application July 27, 1933, Serial No. 48,848

Term of patent 7 years

To all whom it may concern:

Be it known that I, SOREN A. EGEKVIST, a citizen of the United States, residing at Minneapolis, in the county of Hennepin and State of Minnesota, have invented a new, original, and ornamental Design for a Sign, of which the following is a specification, reference being had to the accompanying drawing, forming part hereof, wherein:—

Fig. 1 is a front perspective view of a sign, showing my new design.

Fig. 2 is an end elevation of the same.

I claim:—

The ornamental design for a sign substantially as shown.

SOREN A. EGEKVIST.
